UNITED STATES PATENT OFFICE.

LEVI L. LAMB, OF CHELSEA, MASSACHUSETTS, ASSIGNOR TO HIMSELF
AND SEWELL K. LOVEWELL, OF SAME PLACE.

IMPROVEMENT IN TOOL-RECEPTACLES.

Specification forming part of Letters Patent No. 141,934, dated August 19, 1873; application filed
May 5, 1873.

To all whom it may concern:

Be it known that I, LEVI LYSANDER LAMB, of Chelsea, in the county of Suffolk and State of Massachusetts, have invented a new and Improved Die-Stand, of which the following is a specification:

In the accompanying drawing, Figure 1 represents a vertical section of my improved die-stand on the line *x x*, Fig. 2; and Fig. 2 is a top view of the same, partly in section, on line *c c*, Fig. 1.

Similar letters of reference indicate corresponding parts.

The object of my invention is to furnish, for the use of mechanics, artisans, and machinists, an improved die-stand, into which the different dies for marking metal-work are placed, to be protected thereby against loss or accidental damage. My invention consists of a case of suitable material, surrounding a block with holes, corresponding to the number of dies, into which they are inserted through a perforated top, and inclosed therein by a revolving cover-plate.

A in the drawing represents the outer case, preferably of cylindrical shape and of any suitable material. A short vertical bolt or pin, *a*, placed centrally on the bottom of case *A*, serves as support to spiral spring *b*, which is inserted in a centrally-located vertical recess, *b'*, of block *B*, supporting the same by its spring action. By a recess, *d*, and bolt *e* of case *A*, or other equivalent means, block *B* can readily adjust itself vertically on spring *b*, but is prevented from revolving. Block *B* is of wood, and provided with a series of holes, *f*, arranged symmetrically in the same, for the reception of the dies. These holes *f* are extended into the block as far as required for the length of the dies. A square recess, *g*, on the upper part of block *B*, in the center

of the same, serves as a rest for the round plate *h*, which is connected to square stem *i*, having button *k*. Stem *i* carries, in connection with spiral spring *l*, the inside cover-plate *C*. The outer or top plate *D*, of brass or other suitable material, is screwed, by downward-projecting lugs *m*, to the upper edge of case *A*. Both plates *C* and *D* are perforated to correspond to the number of die-holes *f* in block *B*. The stem *i* projects above top plate *D*, the diameter of aperture *i'* of plate *D* being large enough to permit the square stem *i* to freely turn therein. The inside plate *C* follows readily the rotation of stem *i*, so that its perforations may be brought to coincide with those of block *B* and plate *D*. The dies are placed into the holes of the block when the perforations of the top plates coincide, and a downward pressure and turn being then imparted to the button *k*, carries block *B* downward and rotates plate *C*, so that its perforations shall no longer coincide with those of the top plate and of the block. No die can, therefore, drop out or be taken out till by the reversed operation on button *k* the holes in plate *C* are again brought in line with those in plate *D* and block *B*.

Having thus described my invention, I claim as new and desire to secure by Letters Patent—

The die-block *B*, *f*, movable on guide *e* and spring supported in case *A*, the squared rotary stem *i* swiveled in die-block, the squarely-apertured, perforated, and spring-supported plate *C*, and the perforated top *D*, combined as and for the purpose described.

LEVI LYSANDER LAMB.
